5877X

R. Miller
Thrashing Mach.
Patented Mar 15, 1830.

D. Randolph Miller

Letter Patent

X5877

The claims referred to in these Letter Patent and making part of the same containing a description in the words of the late Randolph Miller himself of his improvement in the Threshing Machine.

It is known that I Randolph Miller of Lancaster, Lancaster County, Pennsylvania have invented an improvement in the machine for threshing grain which is described as follows. This machine consists of 1st the frame. 2nd the cylinder of beaters. 3rd the bed. 4th the hopper feeding roller & cloth. 5th the pulley strips &c for driving the machine. 6th The frame is three feet six inches in length, the side pieces 12 inches wide & under each side piece is a cross piece or girder tenoned into the end posts. The end posts are 3 feet six inches high with four cross pieces or girders, the two lower ones put in with a tenon & mortise from the bottom & the two upper ones let in with a dove tail from the top. At the head end & at one side, the girders extend beyond the frame 9 inches, & upright as plates into the upper & lower girders so as to admit of a multiplying or driving wheel to be placed & run therein. 7th The cylinder of beaters is made to extend along the frame having two circular wooden heads about 15 inches in diameter & two inches thick fixed one near each end on an iron shaft made to turn in bogs placed on the frames side (now only) iron stalk openings are made on each of these heads to let in the ends of the beaters, which have large iron heads made to slide up & down in said openings. These of these beaters are octagonal, and 3rd a half inch in diameter & three are one inch by one & a half made of wrought or cast iron. The two front edges are beaded out being half of the beater to about 3 fourths of an inch, the upper heads are fastened with a square tenon with the dove tail plates above them. The upper girders have a small opening in them to admit of the removal of grain from

cutting the straw. iron wire or hoop about one fourth of an inch thick is drawn on each of the two circular heads to confine the beater in their places, the heads with the beater form a cylinder drawn or cylinder. The several openings in which the beaters are placed admit of their working up & down in such a way that the lower ones fall to the circumference to strike the grain & then converge on the head (to be hereafter described) or in case of resistance from any hard substance will be pushed up towards the centre & admit the substance to pass & not injure the machine. 3. The bed is made to correspond with the cylinder of beaters before described being a section of a circle in which is placed square iron bars having an angle at the end of the beater cut down three eighths of an inch thick to a shoulder and they are so placed in the bed as to beat out the grain, but not to cut the straw when struck by the beaters.

There is also a lining of wood made sufficiently strong to support the iron bars which form the bed & into which the shoulders of the bars are let in by a mortice. 4. The hopper feeding roller

& cloth are made in the usual way and the latter turned by means of straps, cords, & pulleys connected with the driving pulley of cylinder of beaters. There are also two feeding rollers, the lower one is fixed but the upper one rises and falls having a spring over it for that purpose. 5. The multiplying wheel or driving pulley is about 30 inches in diameter, three inches thick also another pulley about 8 inches diameter placed on the axle with the cylinder of beaters. The first turns unguided as supported in bays in the extended girths of the frame before mentioned. A strap passes from the driving pulley to one fixed on the end of the cylinder of beaters & a cord passes from that to the roller that turns the feeding cloth.

Operation. The sheaves of grain being put into the hopper descans on the feeding cloth, the driving pulley being turned by a hand or any other power given for that purpose drives forward the grain on the feeding cloth & the power between the feeding roller to the bed, is obtained by the opening

of beaters, the grain separates from the straw falls thru' between the beaters & the straw is pushed out. What is here claimed as my peculiar invention is the machine as before described, the cylinder of beaters with the mode in which they are made to rise & fall in their above described openings. Also the mode in which the bed is constructed. For a further illustration of my invention I refer to the model and drawing of the same deposited in the Patent Office. In witness whereof I have hereunto subscribed my name at the city of Washington this fifteenth of February, 1830.
